UNITED STATES PATENT OFFICE

WILHELM SCHOELLER, OF BERLIN, GERMANY

VACUUM CLEANER

Application filed October 30, 1931, Serial No. 572,173, and in Germany October 30, 1930.

An object of the present invention is to remedy a defect attaching to many vacuum cleaners, namely, their inability to pick up hairs, threads, fluff and the like, which adhere firmly to the carpet and cannot be removed, except very imperfectly if at all, even by the brushes provided on the nozzles of the cleaner.

The invention provides a hair- and thread-gathering nozzle which can be set on the tubular guide rod of any type of vacuum cleaner and manipulated in precisely the same manner as in the case of carpet sweepers. A gentle reciprocating movement, without any pressure, over any kind of carpet will suffice to loosen the impurities, even when firmly trodden in, so that they will infallibly be carried off by the vacuum current.

20 Typical embodiments of the invention are illustrated in the accompanying drawings.

Fig. 1 is a side elevation of the nozzle.

Fig. 2 is a view of the under side of the nozzle.

25 Fig. 3 is a view of the under side of a modified form.

Figs. 4 and 5 are cross sectional views corresponding to Figs. 2 and 3 respectively.

30 Figs. 6, 7 and 8 illustrate ways of attaching the nozzles to a vacuum cleaner.

a denotes a connecting socket adapted to slip on to the tubular guide rod of any vacuum cleaner with the aid, if necessary, of an adaptor or a reducing piece. *b* is a wood or metal slider, in which longitudinally disposed air passages *c* alternate with strips *d* of non-felting material, such as crêpe rubber, the same being arranged between the lateral terminal pads *e*. The strips *d* either 35 extend over the suction aperture *a'*, as shown in Fig. 2, or are cut away on either side of the constricted transverse suction aperture *a'*, as shown in Fig. 3.

40 The effect of the reduced cross section is to increase the velocity of the air at the suction aperture, with the result that the hairs, threads and the like adhering to the carpet and loosened by the crêpe rubber during the to and fro movement, are infallibly carried away by the suction current. In this way

the nozzle produces in a novel manner the same effect as apparatus provided with beaters.

According to Figs. 6, 7 and 8 the bore of the connecting socket *a* tapers outwards so that either (Fig. 6) the tubular guide rod *B* of certain known vacuum cleaners will fit directly, or (Fig. 7) a biconical adaptor or reducing piece *f*, *g* can be inserted for attachment to another design of tubular guide rod *B'*, or finally (Fig. 8) a sleeve *h* tapering at one end and flared at the other can be inserted to accommodate a close-fitting end of a different pattern of tubular guide rod *B''*. In this way, the same nozzle is applicable to all the usual commercial types of vacuum cleaner.

I claim:-

In a vacuum cleaner, a nozzle having a suction slot extending therethrough, sliding pads disposed laterally of said nozzle at right angles to the suction slot thereof, strips of non-felting material arranged in spaced relation between said pads providing a plurality of paralleling passages at right angles to the suction slot and interrupting the latter, the working surfaces of said strips being at a slightly lesser distance from the nozzle than the working surfaces of said pads.

In witness whereof I have hereunto set my hand.

WILHELM SCHOELLER.
